Primary Examiner — Marianne Pandozzi(74) *Attorney, Agent, or Firm* — Crawford Maunu PLLC(57) **CLAIM**

The ornamental design for a beverage press, as shown and described.

DESCRIPTION

FIG. 1 is a front view of the ornamental design for a beverage press;

FIG. 2 is a left side view thereof;

FIG. 3 is a rear view thereof;

FIG. 4 is a top view thereof;

FIG. 5 is a bottom view thereof;

FIG. 6 is top, left-side perspective view thereof; and,

FIG. 7 is a right side view thereof.
